UNITED STATES PATENT OFFICE.

HERMAN DAVIS, OF NEW ORLEANS, LOUISIANA.

TRUNK.

SPECIFICATION forming part of Letters Patent No. 739,897, dated September 22, 1903.

Application filed June 13, 1903. Serial No. 161,385. (No model.)

To all whom it may concern:

Be it known that I, HERMAN DAVIS, a citizen of the United States, residing at New Orleans, in the parish of Orleans and State of Louisiana, have invented new and useful Improvements in Trunks, of which the following is a specification.

My invention pertains to trunks, and contemplates the provision of a trunk embodying a body, slideable trays, and a cover so constructed and arranged that when the cover is open the trays may be quickly and easily adjusted to afford convenient access to the interior of the body, and this without the necessity of disconnecting or removing the trays from the trunk.

With the foregoing in mind the invention will be fully understood from the following description and claims when taken in connection with the accompanying drawings, in which—

Figure 1 is a side elevation of a trunk constructed in accordance with my invention and comprising two covers and two vertical series of trays, the same being shown with the covers open and the trays slid into the covers. Fig. 2 is a longitudinal vertical section illustrating the trays and the covers in their closed positions. Fig. 3 is a detail transverse section taken in the plane indicated by the broken line 3 3 of Fig. 2. Fig. 4 is a side elevation of a modified trunk, the same being shown with one of its covers open and the series of trays complementary to said cover slid into the same. Fig. 5 is a perspective view of a modified form of trunk which comprises but one vertical series of trays and but one cover, the same being shown with the cover open. Fig. 6 is a longitudinal vertical section of the same with the cover closed. Fig. 7 is a transverse section illustrating the cover as open and partly broken away, and Fig. 8 is an enlarged view illustrating the tray-supporting devices of the trunk shown in Fig. 7 removed from the trunk.

Referring by letter to said drawings, and more particularly to Figs. 1 to 3 thereof, A is the body, B B the slideable trays, and C C the covers, of the trunk constituting the preferred embodiment of my invention. The body, which may be made of any material suitable to the purpose of the invention, is

rectangular in form and comprises side walls a, the upper edges of which are inclined downwardly from their vertical centers to 55 their ends, as indicated by b, end walls c, corresponding in height to the ends of the side walls and having beveled upper edges, Fig. 2, and false side walls d, fixed at the inner sides of said side walls and having longitudinal guideways or grooves e at their inner sides, Fig. 3. The slideable trays are arranged in two vertical series between the false side walls d of the body and are provided with flanges f, disposed in the guideways e of said 65 walls d, so as to permit of their being readily slid in the direction of the length of the trunk. The covers respectively comprise end walls g, beveled in conformity with and hinged to the end walls c of the body, top 70 walls h, disposed at right angles to the walls g, and side walls i, having edges j corresponding in inclination and length to the edges b of the side walls of the body and adapted when the covers are closed to rest on said edges b. 75

D D are hinges through the medium of which the covers C are connected to the end walls c of the body A. These hinges in the preferred embodiment of my invention are constructed and arranged as shown in Figs. 80 1 and 2, so as to limit the downward movement of the covers and support the same in the position shown in Fig. 1. I desire it understood, however, that the hinges may be of any suitable construction and that any 85 suitable means may be employed for supporting the covers in the position stated without involving a departure from the scope of my invention.

E is a lock member attached to the wall h 90 of one cover C adjacent to the free end of the cover, and F a lock member connected to the wall h of the other cover C in position to engage the first-mentioned member when the covers are closed, as shown in Fig. 2. The 95 said lock members are preferably employed to prevent casual and unauthorized opening of the covers C; but it is obvious that other means may be employed for this purpose without departure from the scope of my invention.

In virtue of the construction of my improved trunk it will be observed that when the several trays are in the positions shown

in Fig. 2 and the covers are closed and connected together said covers will serve to entirely inclose and hold the trays against casual movement; also, that when the covers are disconnected and swung down into the positions shown in Fig. 1 and the two vertical series of trays are moved in opposite directions until the trays bring up against the walls h of the covers ready access is afforded to the interior of the body of the trunk for the introduction or removal of goods. It will further be observed that when the trays are moved outwardly until their outer ends abut against the walls h of the covers the inner portions of their flanges f will remain in the guideways e of the false side walls d , and hence said trays will be retained in their proper relative positions in the trunk and may be readily returned to the positions shown in Fig. 2 with but little effort. Each of the trays of each vertical series may when desired be moved independently of the other trays of the series, this in order that access may be readily gained to the interiors of all of the trays.

The grooves e in the false side walls d of the body A might be disposed horizontally without departing from the scope of my invention. I prefer, however, to incline said grooves slightly upward from the vertical center of the body to the ends thereof, as shown in Figs. 1 and 2, this in order to permit of the trays being very easily moved inward to the positions shown in Fig. 2 preceding to closing the covers C .

While I prefer to make the trays of a length equal to about one-half of that of the body and to arrange them in two vertical series, as shown and described, I desire it understood that the trays may be made of substantially the same length as the body or of any other suitable length without involving departure from the scope of my invention.

Referring to the modified trunk shown in Fig. 4, A' is the body of the trunk, B' B' the slideable trays, and C' C' the covers. In this embodiment of my invention the body comprises rectangular side walls a' , having guideways e' at their inner sides similar to the guideways e (shown in Figs. 1 to 3) and end walls c' of about the proportional height shown. The trays B' are similar in construction to the trays B , before described, and are similarly arranged in the body, while the covers C' respectively comprise end walls g' , connected by hinges D to the body-walls c' , top walls h' , disposed at right angles to the walls g' , and side walls i' , arranged when the covers are closed to rest on the upper edges j' of the side walls of the body. One of the covers C' is provided with a lock member E and the other with a complementary lock member F for the purpose before described.

As will be readily observed by reference to the drawings, the construction shown in Fig. 4 is used in the same manner as that shown in Figs. 1 to 3 and is possessed of practically

all of the advantages of the latter construction. While this is so, it will be noticed that the construction shown in Fig. 4 is a material simplification of that disclosed by Figs. 1 to 3 in that it lacks false side walls.

Referring now to the modified construction shown in Figs. 5, 6, and 7, A^2 is the body, B^2 B^2 the slideable trays, and C^2 the cover. The body is made up of a vertical wall c^2 , a vertical wall c^3 , of less height than the wall c^2 , having its upper edge beveled, side walls a^2 , having their upper edges inclined from the upper edge of the wall c^2 to the upper edge of the wall c^3 , and false side walls d^2 , fixed at the inner sides of the walls a^2 and having guideways e^2 in their inner sides. The trays B^2 are arranged in a vertical series in the body and have flanges f^2 movable in the guideways e^2 of the walls d^2 . The uppermost tray of the series is beveled at r in order to enable the cover to clear the same when said cover is closed. The cover is connected to the wall c^3 of the body through the medium of hinges D , such as before described, and is made up of an end wall g^2 , a wall g^3 of less width than the wall g^2 , a top wall h^2 , and side walls i^2 , having edges j^2 , inclined in conformity with and arranged to rest on the inclined edges of the body-walls a^2 . When the cover C^2 is supported in the position shown in Fig. 5 by the hinges D , it will be observed that the trays B^2 may be slid into said cover, so as to afford access to the interior of the body A^2 ; also, that each of the trays may be slid into the cover and back into the body independent of the other trays. It will further be observed that when the trays are moved into the cover C^2 until they bring up against the wall h^2 of said cover portions of their flanges f^2 will remain in the guideways e^2 of the body, and hence they will be supported and retained in their proper relative positions ready to be expeditiously slid back into the body. The guideways e^2 are inclined slightly, as clearly shown in Fig. 7, for the purpose before stated—viz., to render easy replacing the trays in the positions shown in Fig. 7. Any suitable means—such, for instance, as the lock members E and F , before described—may be employed to secure the cover C^2 in its closed position.

In Figs. 7 and 8 I have illustrated means for assisting in the support of the two upper trays B^2 when the same are drawn from the body into the cover. Said means comprise a plate m^2 , fixed to the inner side of the cover-wall h^2 , and arms n^2 p^2 of different lengths, connected to said plate by hinges q^2 of such construction that when the arms are swung from a position flat against the plate to a position at right angles thereto, Fig. 7, the arms will be supported in the latter position. The plate m^2 is provided with spring-keepers r^2 , designed to hold the arms n^2 p^2 flat against the plate when the trunk is closed, while the said arms are equipped adjacent to their free ends with antifriction-rollers s^2 , adapted to

render easy the movement of the trays when the latter are run out on the arms. Precedent to swinging the cover C^2 to its closed position the arms $n^2 p^2$ are swung against the plate m^2 and secured in such position through the medium of the keepers r^2 , so as not to interfere with the closing of the cover. When the cover is opened, the arms $n^2 p^2$ are disengaged from the keepers r^2 and are swung down into the position shown in Fig. 7. In this latter position it will be noticed that the arms will form an efficient support for the two upper trays when the latter are moved out of the body.

15 It is obvious that when desired the covers of all of the embodiments of my invention herein disclosed may be equipped with tray-supporting devices similar to that shown in Figs. 7 and 8 without departure from my invention.

In all of the several embodiments of my invention it will be noticed that the cover is hinged to the body at a point below nine inches from the extreme top of the trunk; also, that 15 an opening is provided between the side walls above the point of connection of the cover, through which the trays may be moved to afford access to the interior of the body.

It will be readily appreciated from the foregoing that while the several embodiments of my invention are simple and compact in construction they are possessed of large capacity.

I have entered into a detailed description of the construction and relative arrangement 35 of the parts embraced in the present embodiments of my invention in order to impart a full, clear, and exact understanding of the same. I do not desire, however, to be understood as confining myself to such specific construction and arrangement of parts, as such changes or modifications may be made in practice as fairly fall within the scope of my invention as claimed.

Having described my invention, what I 45 claim, and desire to secure by Letters Patent, is—

1. In a trunk, the combination of a body having side walls, and openings between said side walls at its ends, and also having longitudinal guideways extending to the openings, covers hinged to the ends of the body, below the top of the trunk, and respectively comprising an end wall, a top wall and side walls, one or more trays arranged between the side walls of the body, and movable in the guideways and through the openings at the ends thereof; said tray or trays being of a greater length than the distance between the ends of the side walls of the body and the top walls 55 of the covers when said top walls are in upright positions, and means for supporting the covers when they are open and their top walls rest in an upright position, whereby said top walls are enabled to prevent the withdrawal 65 of the tray or trays from the guideways of the body.

2. In a trunk, the combination of a body

having side walls, and an opening between said side walls at one end, and also having vertical series of longitudinal guideways at 70 the inner sides of said side walls, extending to the opening, trays arranged one above the other between the side walls, and movable in the guideways thereof, a cover hinged to the body, below the top of the trunk, and 75 comprising an end wall, a top wall and side walls, and means for supporting the cover when it is open and its top wall rests in an upright position, whereby said top wall is enabled to prevent the withdrawal of the trays 80 from the guideways of the body.

3. In a trunk, the combination of a body having side walls and an opening between said side walls at one end, and also having longitudinal guideways at the inner sides of 85 said side walls, extending to the opening, one or more trays arranged between the side walls, and movable in the guideways thereof, a cover hinged to the body, below the top of the trunk, and comprising an end wall, a top wall disposed at right angles to the end wall, and side walls, and means for supporting the cover 90 when it is open and its top wall rests in an upright position, whereby said top wall is enabled to prevent the withdrawal of the tray 95 or trays from the guideways of the body.

4. In a trunk, the combination of a body having side walls, and openings between said side walls at its ends, and also having longitudinal guideways, at the inner sides of the 100 side walls, extending to the openings; said guideways being slightly inclined upward from the vertical center of the body to the ends thereof, covers hinged to the ends of the body, below the top of the trunk, and respectively comprising an end wall, and a top wall disposed at an angle to the end wall, and trays 105 arranged between the side walls of the body, and movable in the guideways thereof; said trays being of a greater length than the distance between the ends of the side walls of the body and the top walls of the covers.

5. In a trunk, the combination of a body comprising side walls having inclined upper edges, an end wall corresponding in height to 115 the lower ends of the side walls, and false side walls fixed at the inner sides of the side walls, and extending above the end wall, and having longitudinal guideways, one or more slideable trays arranged between the false side 120 walls of the body and in the guideways thereof, and a cover comprising an end wall hinged to the end wall of the body, a top wall, and side walls having edges inclined in conformity with and adapted to rest on the inclined edges 125 of the side walls of the body.

6. In a trunk, the combination of a body comprising side walls having inclined upper edges, an end wall corresponding in height to 130 the lower ends of the side walls, and false side walls fixed at the inner sides of the side walls, and extending above the end walls, and having longitudinal guideways, one or more slideable trays arranged between the false side

walls of the body and in the guideways thereof, a cover comprising an end wall hinged to the end wall of the body, a top wall, and side walls having edges inclined in conformity with and 5 adapted to rest on the inclined edges of the side walls of the body, and means for supporting the cover when its top wall is in an upright position.

7. In a trunk, the combination of a body 10 comprising side walls having inclined upper edges, an end wall corresponding in height to the lower ends of the side walls, and false side walls fixed at the inner sides of the side walls, and extending above the end wall, and having 15 longitudinal guideways, one or more slidable trays arranged between the false side walls of the body and in the guideways thereof, a cover comprising an end wall, a top wall, and side walls having edges inclined in conformity 20 with and adapted to rest on the inclined edges of the side walls of the body, and one or more hinges, connecting the cover and the end wall of the body, and adapted to support the cover.

8. In a trunk, the combination of a body 25 comprising side walls having upper edges *b* inclined downwardly from their vertical centers to their ends, end walls corresponding in height to the lower ends of the side walls, and false side walls fixed at the inner sides 30 of the side walls, and extending above the end walls, and having longitudinal guideways, one or more slidable trays arranged between the false side walls of the body and in the guideways thereof, and covers comprising 35 end walls hinged to the end walls of the body, top walls, and side walls having edges inclined in conformity with and adapted to rest on the inclined edges of the side walls of the body.

40 9. In a trunk, the combination of a body comprising side walls having upper edges *b* inclined downwardly from their vertical centers to their ends, end walls corresponding in height to the lower ends of the side walls, 45 and false side walls fixed at the inner sides of the side walls, and extending above the end walls, and having longitudinal guideways, covers comprising end walls hinged to

the end walls of the body, top walls, and side walls having inclined edges, means for supporting the covers with their top walls in an upright position, and one or more slidable trays arranged between the false side walls of the body and in the guideways thereof; said tray or trays being of a greater length 55 than the distance between the ends of the false side walls and the tops of the covers when the latter are open.

10. In a trunk, the combination of a body 60 having side walls and an opening between said side walls at one end, and also having longitudinal guideways, at the inner sides of said side walls, extending to the opening, one or more trays arranged between the side walls, and movable in the guideways thereof, 65 a cover hinged to the body, at a suitable point below the top of the trunk, and adapted, in its open position, to receive the tray or trays when the same are slid outwardly, and means carried by the cover for supporting the 70 tray or trays when the latter are slid outwardly.

11. In a trunk, the combination of a body 75 having side walls and an opening between said side walls at one end, and also having longitudinal guideways, at the inner sides of said side walls, extending to the opening, one or more trays arranged between the side walls, and movable in the guideways thereof, a cover hinged to the body, at a suitable point 80 below the top of the trunk, and adapted, in its open position, to receive the tray or trays when the same are slid outwardly, a plate fixed to the top wall of the cover, one or more arms hinged to the plate, means for supporting 85 said arm or arms at an angle to the plate, and means for holding the arm or arms against the plate to permit of the cover being closed.

In testimony whereof I have hereunto set 90 my hand in presence of two subscribing witnesses.

HERMAN DAVIS.
